CHURN

Filed April 2, 1926

G. O. Laney
BY *Victor J. Evans*
INVENTOR
ATTORNEY

UNITED STATES PATENT OFFICE

GEORGE O. LANEY, OF HAMBURG, OKLAHOMA

CHURN

Application filed April 2, 1926. Serial No. 99,345.

This invention relates to churning, the general object being the provision of a supporting bracket for a crank arm and gear carried upon its inner end for support upon the cover for the churn and which gear meshing at appropriate points thereon with independently mounted gears in turn associated with the dashers or agitating arms within the churn whereby a single operation in the rotation of the crank arm will rotate the dasher or agitating arms in opposite directions whereby the cream within the churn will be more quickly and easily converted into butter owing to the reverse directions of momentum of the agitating arms.

With the above and other objects in view, the invention further includes the following novel features and details of construction, to be hereinafter more fully described illustrated in the accompanying drawings and pointed out in the appended claim.

In the drawing:

Figure 1 is a vertical sectional view taken through the invention.

Figure 2 is an elevation of the invention as applied upon the churn.

Figure 3 is a transverse section taken on line 3—3 of Figure 1.

Figure 4 is a similar view taken on line 30 4—4 of Figure 1.

Figure 5 is a vertical sectional view taken on line 5—5 of Figure 1.

Referring to the drawing in detail, wherein like characters of reference denote corresponding parts, the reference character 10 indicates a jar or receptacle having a closure lid or cover 11 threaded or otherwise secured to the neck therefor and which includes spaced parallel strips 12 cut therefrom for the reception and positioning of the oppositely and outwardly extending end portions 13 of a substantially inverted U-shaped bracket or support 14. The end portions 13 terminate in curved outer ends for fitting engagement with the edge of the cover 11 as clearly shown in Figures 1 and 2. A vertically disposed shaft 15 being journaled within an inwardly extending transversely disposed apertured ear struck from one side of the bracket 14, and said shaft is provided with a

plurality of lugs 17 extending outwardly therefrom for the purpose of supporting the shaft on the ear 16 as clearly shown in Figure 1 of the drawings. A gear indicated by the reference numeral 18 is mounted upon the upper end of the shaft which extends through a sleeve 19 mounted independently of the shaft and this sleeve has secured thereto a gear 20. The sleeve is mounted for rotation in a collar secured to the cover 11 and is formed with a bead engageable with the collar whereby the sleeve is supported as shown. The sleeve is further provided with a rectangular portion 21 upon its lower end as clearly shown in Figure 4 of the drawings and is mounted for rotation in a sleeve secured in an opening formed in the cover or lid 11. The rectangular portion 21 is received within opposed substantially V-shaped portions 22 provided in the hilt or upper horizontal disposed portion 24 of a pair of downwardly extending agitator arms 25 in a manner whereby when the sleeve 19 is moved, like movement will be imparted to the agitator arms 25. The V-shaped portions 22 are formed upon the opposite sides of a longitudinal slit arranged in the horizontal disposed portion 24 as suggested in Figure 1. The shaft 15 is provided with a longitudinally disposed slot 26 arranged in its lower portion for receiving an additional agitator blade 27 which is secured in the slot as best shown in Figure 5 of the drawings.

Rotatably mounted within a sleeve 28 secured in and extending outwardly from one side of the bracket 14 is the inwardly extending end portion of a crank shaft 30, the inner end of this portion 29 has secured thereto a relatively large gear 31 which is disposed in mesh with the respective gears 18 and 20 upon the shaft 15 and sleeve 19 as shown.

Secured to the cover or lid 11 and passing therethrough as best shown in Figure 2 of the drawings is a tube 32.

From the above description and disclosure of the drawings, it will be obvious that in the operation of the device that upon rotation of the gear 31 by the crank arm 30 the respective gears 18 and 20 will be caused to rotate

in opposite directions whereby the agitator arms 25 and 27 respectively will be caused to operate in like manner whereby the contents of the receptacle 10 will become more readily stirred, mixed and churned and the action attained thereby will transform cream contained in the receptacle into butter products in less time than is usually taken in the operation of singularly operable and rotating agitators.

The invention is susceptible of various changes in its form, proportions and minor details of construction, and the right is herein reserved to make such changes as properly fall within the scope of the appended claim.

Having thus described the invention, what is claimed is:—

In a churn, a receptacle, a closure for said receptacle, upwardly extending spaced parallel arranged strips cut from said closure, a relatively narrow substantially inverted U-shaped bracket, oppositely disposed outwardly extending end portions formed with the lower ends of the arms of said bracket at right angles thereto and being received between the strips and portions of the closure, curved outer ends formed with said end portions and being arranged for fitting engagement about the upper edge of the closure for cooperation with the strips for securing the bracket to the closure, agitating means, means for supporting said agitating means for rotation and carried by the bracket and closure respectively, and means for rotating said agitating means.

In testimony whereof I affix my signature.
GEORGE O. LANEY.
